UNITED STATES PATENT OFFICE.

GEORGE A. KAMPMANN, OF BRAINERD, MINNESOTA.

WATERPROOFING DEVICE.

1,423,857.

Specification of Letters Patent. Patented July 25, 1922.

Application filed October 1, 1919. Serial No. 327,645.

To all whom it may concern:

Be it known that I, GEORGE A. KAMPMANN, a citizen of the United States, residing at Brainerd, in the county of Crow Wing 5 and State of Minnesota, have invented certain new and useful Improvements in Waterproofing Devices, of which the following is a specification, reference being had therein to the accompanying drawing.

0 This invention relates particularly to waterproofing or weather strips adapted for use with windows having swinging sash, doors, or other closures, and it is an object of the invention to provide a formation and 15 arrangement of parts that will prevent water, under all conditions of weather, from entering between the closure and a sill or other abutting part.

The parts of the device are so formed that 20 water that tends to enter will be drained off to the outside.

The device in its entirety may be made conveniently and economically of sheet metal, and it is susceptible of being put into 25 place easily with a few screws, nails, or other suitable fasteners, and without material alteration of the parts with which it is associated.

When read in connection with the description herein, the details of construction and 30 arrangement of parts contemplated by the invention will be apparent from the accompanying drawing, forming part hereof, wherein an embodiment of the invention is 35 disclosed, for purposes of illustration.

While the disclosures herein now are considered to exemplify a preferable embodiment of the invention, it is to be understood that it is not the intention to be limited necessarily thereto in interpretation of the 40 claims, as alterations and adaptations within the limits of the claims may be made without departing from the nature and spirit of the invention.

45 Like reference-characters refer to corresponding parts in the views of the drawing, of which—

Figure 1 is a sectional view of the device as applied to a casement-window;

50 Fig. 2 is a fragmentary outside elevation; and

Fig. 3 is a sectional view of the device as applied to a casement-window having a sill with the major portion of its top surface in a 55 horizontal plane.

Having more particular reference to the

drawing, A designates a sill at the bottom of an opening that is closed by a swinging sash or the like B.

The waterproofing device includes a member 4 adapted to be secured to the sill. This member has a substantially flat web portion 5 arranged to extend across that portion of the sill that is directly below the sash when closed and to be held tightly down against the sill. At the outer edge of the flat portion, the material of the member extends downwardly and thence upwardly, whereby a gutter 6 is provided, and in the bottom of the gutter at suitable intervals are drain- 70 vents 7 arranged to permit water to drop outside of the window-opening. The material of the member extends inwardly and with an upward inclination with respect to the bottom of the sash from the outside and upper portion of the gutter as a flange 8, and the upper or free edge of the flange extends upwardly as a lip 9, which has a tendency to deter the passage of water into the other member of the device. 80

When the sill does not have an outside drop or abutment, such as shown at A' in Fig. 1, to accommodate the downwardly-extending gutter 6, the member 4 may be attached to a strip A'' secured to and extending across the sill under the sash, as shown by Fig. 3.

Another member 10 is arranged to be attached to the sash or the like and to cooperate with the fixed member 4. The member 10 includes a substantially flat web portion 11 arranged to be secured tightly against the outside of the sash along the edge portion adjacent to the sill; and, in order to contribute to the tightness of the joint between the web and the sash and to the firmness of the association of those parts, the free edge portion of the webs is bent inwardly as a flange 12, which is let into the material of the sash. The material of the member along the opposite or lower edge of the web is bent upon itself slightly upwardly to form a drip-lip 13, and thence it extends inwardly of the sash as an upper wall 14 and thence outwardly as an opposite wall or flange 15, which has its free edge portion bent downwardly as a drip-lip 16. A substantially U-shaped pocket 17 thus is provided that extends inwardly of the sash, the material of the latter being cut away to receive the 110 pocket, and the wall 14 and the inner portion of the pocket seat tightly against the sash.

material. The flange 15 has a downward inclination corresponding approximately to the inclination of the flange 8 of member 4; and, when the sash or the like carrying member 10 is closed, the flange 15 extends under flange 8.

The member 4 is held securely in position by nails, screws, or other similar fastenings driven through the web 5 into the sill or 10 into the strip A'', and the member 10 by similar fastenings driven into the sash through the web 11 and through the material at the end of the pocket 17.

It will be seen that, when the sash or the 15 like is closed, the flange 15 thereon extends under the flange 8 fixed on the sill, and that water driven in over the latter flange and its lip 9 will pass into pocket 17, whence it will drain over flange 15 into the gutter 6 and out through the vents 7, and thereby will be 20 prevented from entering the window or other opening between the sash or its equivalent and the sill.

The two members of the device are so relatively formed that their respective flanges do not contact with each other, and thus liability of the parts binding, catching, or otherwise interfering with the closing and opening of the sash or the like is avoided.

Having thus described my invention, what I claim as new, and desire to secure by Letters Patent, is—

1. As a part of a weatherstrip device, a member comprising a substantially flat web arranged to be secured against the outside of a closure and having its material extending inwardly from the lower edge of the web as the upper wall of a pocket portion arranged to seat against material of the closure to which the member is attached, and having its material also extending outwardly and downwardly from the inner end of the pocket portion as the lower wall thereof.

45 2. As a part of a weatherstrip device, a member comprising a substantially flat web arranged to be secured against the outside of a closure and having its upper edge disposed inwardly and capable of being let into the material to which the member is attached, the material of the member extending inwardly from the lower edge of the web as the upper wall of a pocket portion arranged to seat against material of the closure to which the member is attached, and

50 55

the material of the member also extending outwardly and downwardly from the inner end of the pocket portion as the lower wall thereof.

3. As a part of a weatherstrip device, a sheet-metal member comprising a substantially flat web arranged to be secured against the outside of a closure, the material of the member along the lower edge of the web being bent upon itself and affording a drip-lip and thence extending inwardly as the upper wall of a pocket portion arranged to seat against material of the closure to which the member is attached, and the material of the member also extending outwardly and downwardly from the inner end of the pocket as the lower wall thereof.

4. As a part of a weatherstrip device, a member comprising a substantially flat web arranged to be secured against the outside of a closure, the member having its material extending inwardly from the lower edge of the web as a wall of a pocket portion arranged to seat against material of the closure to which the member is attached, and the material of the member also having its material extending outwardly and downwardly from the inner end of the pocket portion as the lower wall thereof and having the outer edge of the latter wall disposed downwardly as a drip-lip.

5. As a part of a weatherstrip device, a sheet-metal member comprising a substantially flat web arranged to be secured against the outside of a closure and having its upper edge portion turned inwardly and capable of being let into the material to which the member is attached, the material of the member along the lower edge of the web being bent upon itself and affording a drip-lip and thence extending inwardly as the upper wall of a pocket portion arranged to seat against the material of the closure to which the member is attached, and the material of the member also extending outwardly and downwardly from the inner end of the pocket portion as the lower wall thereof and having its lower edge portion bent downwardly as a drip-lip.

In testimony whereof I affix my signature in presence of two witnesses.

GEORGE A. KAMPMANN.
